United States Patent Office

Des. 198,332
Patented June 2, 1964

198,332

GRILL

James Teague, Jr., 1533 Hawthorn Lane, Glenview, Ill.,
and Victor A. Peteril, 509 Fair Oak, Oak Park, Ill.

Filed Oct. 14, 1963, Ser. No. 76,976

Term of patent 14 years

(Cl. D44—1)

FIG. 1 is a perspective view of a grill embodying our new design;

FIG. 2 is an enlarged front elevational view of the grill;

FIG. 3 is a side elevational view of the grill to the same scale as FIG. 2;

FIG. 4 is a top plan view of the grill; and

FIG. 5 is a rear elevational view.

We claim:

The ornamental design for a grill, substantially as shown.

References Cited in the file of this patent

UNITED STATES PATENTS

D. 139,751	Springwell	Dec. 19, 1944
D. 178,247	Knapp	July 10, 1956
D. 179,864	Smith	Mar. 12, 1957